UNITED STATES PATENT OFFICE

2,042,929

ELECTRON DISCHARGE DEVICE AND
ANODE THEREFOR

George M. Dinnick, Bloomfield, N. J., assignor
to Westinghouse Lamp Company, a corpora-
tion of Pennsylvania

Original application June 1, 1933, Serial No.
673,865. Divided and this application Decem-
ber 28, 1935, Serial No. 56,447

3 Claims. (Cl. 250—27.5)

This invention relates to electric discharge de-
vices and more particularly to devices of this
character adapted to be employed in the radio
field, and constitutes a division of my copending
5 application Serial No. 673,865, filed June 1, 1933.

In its more specific aspect the invention is
directed to an improved electric discharge device
and especially to an improved anode that may be
employed therein. Heretofore it has been cus-
10 tomary to employ electric discharge devices com-
prising an anode, a cathode and a grid in the
radio receiving and other fields.

The anode generally in tubular form com-
prises a plurality of similar plates secured to-
15 gether by a nut and bolt arrangement or having
interlocking means serving this purpose. As dis-
tinguished from the prior art my invention is
directed to a composite unitary hollow anode
having excellent heat radiating properties and
20 being adapted to be readily manufactured and
mounted in an electric discharge device such as
a radio tube.

My invention is further directed to an im-
proved discharge tube which embodies my im-
25 proved anode and may be readily seasoned by
induction heat treatment without the necessity
of electron bombardment. Because of my novel
anode, the cathode and grid of a radio tube em-
bodying the same are suitably treated when a
30 high frequency induction coil surrounds the tube
containing them.

An object of my invention is to provide an im-
proved electric discharge device which may be
readily manufactured and seasoned.

35 Another object of my invention is to provide
an improved anode which may be readily manu-
factured and mounted in a discharge device and
which has good heat radiating properties.

Other objects and advantages of my invention
40 will become readily apparent from the following
description and drawing wherein:

Figure 1 represents a longitudinal front view
with parts broken away of a discharge device
embodiment my invention and with the envelope
45 of the device not shown;

Figure 2 represents a perspective view of an
anode embodying my invention;

Figure 3 represents a horizontal cross sectional
view of Fig. 2 taken at about the mid-length
50 thereof;

Figure 4 represents a horizontal cross sectional
view of an anode embodying my invention and
being a modification of the anode shown in Fig. 2.

As illustrated, the electric discharge device in
55 the form of a radio tube comprises an envelope

consisting of a body portion (not shown) and a
re-entrant stem 10 extending upwardly into said
body portion. Said re-entrant stem 10 has a
press 1 in which are secured a plurality of spaced
conductors 12, 13 and 14 extending interiorly and 5
exteriorly of said envelope.

A flexible metallic band 15 is wrapped around
the stem 10 below the press thereof and is in fric-
tional engagement therewith by means of the nut
and bolt arrangement 16. At one side of said 10
press are a plurality of standards 17 and 18 which
are welded to said band 15 and extend upwardly
in said envelope. A corresponding pair of stand-
ards are secured to said band at the other side of
said press. The standards 17 and 18 converge 15
and are welded to each other at that portion
where the standard 18 terminates. The stand-
ard 17 has the major portion thereof extending
upwardly in said envelope and substantially
parallel to the longitudinal axis thereof an ap- 20
preciable distance above the upward limit of the
standard 18.

A cruciform press 19 having diametrically dis-
posed openings in one of the cross arms thereof
has the upper portion of the standards 17 extend- 25
ing through these openings, with the cross arm
of the insulator 19 resting upon the upper limit of
the standards 18. The other cross arm of the
insulator 19 has a plurality of openings therein
adapted to accommodate conductors and sup- 30
ports 20, 21, 22 and 23. A suitably sized wire is
helically wound around the conductors 20, 23,
and serves as the grid element of the tube. An
M-shaped filament, having its ends secured to the
conductors 21 and 22 and having its upper bight 35
portions secured to a pair of hooks, hereinafter
described, serves as the cathode element. A
small shallow carbon disk 24 having a circular
opening therein is mounted on each of the stand-
ards 17. 40

In accordance with my invention a rigid com-
posite unitary anode 25 surrounds the grid and
cathode. The anode comprises an elongated hol-
low member consisting of two flat sides 26 of
sufficient width and arranged parallel to each 45
other and integral with two curved portions 27
forming the other sides. A cross sectional view of
said anode which is in the form of a hollow shell
at right angles to its major axis, is in the form
of a rectangle having rounded ends. At the mid- 50
width of each of said flat sides and extending
along the entire length thereof are outwardly
extending lateral extensions 30. Each extension
30 is of appreciable cross-sectional area and has
a longitudinally disposed opening 31 along the 55

entire length thereof parallel to the longitudinal axis thereof. The opening 31 may be cylindrical, as shown in Figure 3, or a groove, as shown in Figure 4.

5 It is also within the purview of my invention to employ a structure similar in all respects to that shown in Figure 2 except that there are no openings or grooves in the lateral extensions. These lateral extensions may be solid throughout their cross section and any suitable means such as clamps, may be in contact therewith to hold the same in position.

The anode, which is a single element structure, may be readily formed by a machining operation 15 or it may be manufactured by extruding a suitable plastic of graphite and easily carbonizable binder after which extrusion step the plastic element may be fired to complete carbonization and dryness. This composite unitary anode is composed 20 essentially of graphite for good heat radiating properties which is one of the desirable features of an anode.

My anode, as heretofore described, may be readily assembled in an electric device by merely 25 sliding the standards such as 17 through the longitudinally disposed openings 31. The diameter of the openings is substantially the same as that of the standards 17. A small shallow disk 24', the same type as the disks heretofore 30 described, has openings therein through which the upper portion of the standards 17 extend so that these disks rest upon the lateral extensions of the anode. A cruciform insulator 32, similar 35 to the insulator 19, also has openings therein adapted to accommodate the standards 17 which extend therethrough and project upwardly therefrom.

The insulator 32 has openings adapted to accommodate the conductors 20 and 23 which extend therethrough. Short cross bars 33 are welded 40 to the upper portion of the conductor 20 immediately adjacent and above the insulator 32. A cross bar is also welded to the lower portion of the conductor 23 immediately adjacent and below 45 the insulator 19. Hooks 29, which support the upper bights of the filament, have the shanks thereof integral with springs which rest in small recesses in the upper face of the insulator 32, with

the shanks thereof extending through openings in said insulators.

Resting upon the insulator 32 and adjacent the outer portions thereof and welded to each of the standards 17 above the insulator is an inverted 5 U-shaped rod 35 having the sides thereof welded to the standards 17 and 18 at the places where the sides of said U-shaped rods and standards intersect. A conductor 36 is electrically connected to one of the standards 17 and is hermetically 10 sealed to a portion of the envelope other than the press and extends exteriorly of said envelope to form a terminal for the anode.

It is apparent that this invention is susceptible to modifications and it is not to be limited by the 15 exact structure herein disclosed, but only by the prior art.

What is claimed:

1. An electron discharge device including a stem, an anode, a cathode, said anode surrounding said cathode, said anode being a composite single unit composed of carbon, said anode being in the form of a hollow tubular shell with extensions thereon and a plurality of standards carried by said stem, said extensions having openings therein, said standards extending into said openings.

2. An electron discharge device including a stem, a cathode, a grid, a pair of standards carried by said stem, and an anode, said anode being a single piece and being composed of a composite graphite unit, said anode being of tubular form with lateral extensions having openings therein in the direction of the length thereof, said standards extending into said openings.

3. An electron discharge device comprising a stem, a plurality of standards carried by said stem, an anode, a cathode and a grid, said anode having lateral extensions and surrounding said cathode and grid, said anode being in the form of a single piece hollow shell, said lateral extensions extending along the length of said shell and having openings therein adapted to accommodate said standards, said standards being located in said openings, said anode being a composite unit of graphite.

GEORGE M. DINNICK.

DISCLAIMER

2,042,929.—*George M. Dinnick*, Bloomfield, N. J. ELECTRON DISCHARGE DEVICE AND ANODE THEREFOR. Patent dated June 2, 1936. Disclaimer filed November 10, 1937, by the patentee; the assignee, *Westinghouse Electric & Manufacturing Company*, consenting.

Hereby enters this disclaimer to claims 1, 2, and 3 of said patent.
